FIG. 1

FIG. 4

FIG. 1 is a perspective view of a combined outlet box and escutcheon plate with recessed push-buttons for a table top or similar article, showing my new design;

FIG. 2 is a perspective view thereof from the opposite side showing one of the push-buttons in an operative position;

FIG. 3 is a top plan view thereof; and

FIG. 4 is a side elevational view, the opposite side being substantially a mirror image thereof.

The dominant features of my new design are shown in solid lines in the drawing.

I claim:

The ornamental design for a combined outlet box and escutcheon plate with recessed push-buttons for a table top or similar article, substantially as shown and described.
